Joshua Hendy

United States Patent Office.

JOSHUA HENDY, OF SAN FRANCISCO, CALIFORNIA.

Letters Patent No. 78,089, dated May 19, 1868.

IMPROVED CONCENTRATOR.

The Schedule referred to in these Letters Patent and making part of the same.

TO ALL WHOM IT MAY CONCERN:

Be it known that I, JOSHUA HENDY, of the city and county of San Francisco, State of California, have invented certain new and useful Improvements in Concentrators; and I do hereby declare the following description, and accompanying drawings are sufficient to enable any person skilled in the art or science to which it most nearly appertains to make and use my said invention or improvements without further invention or experiment.

The nature of my invention is to provide an improved concentrator for saving finely-divided quicksilver, amalgam, and gold from the sands, and for concentrating and saving the sulphurets contained in ores, and consists of an iron frame, of peculiar construction, which holds an oscillating-pan, having a curvilinear bottom, with a groove around the inner periphery, which gradually declines from a given point to the opposite or discharging-point.

My invention also relates to a distributor or distributors and stirrers, which are operated by the same power which moves the pan, and through which the pulp passes into the pan, the heavier particles settling in the annular groove, displacing the lighter particles of sand by their gravity and the centrifugal force, while the current of water and the sand and debris tend towards the central discharge-opening, through which they pass out, and at the same time the stirrers agitate the surface of the pan, and prevent the packing of the material which is being treated.

Also my invention relates to a self-discharging apparatus, and the peculiar construction of the crank-pin attachment, which accommodates itself to the circular line of the oscillations of the pan.

To more fully illustrate and describe my invention, reference is had to the accompanying drawings, and letters marked thereon, forming a part of this specification, of which—

Figure 1 is a plan.

Figure 2 is a side sectional elevation.

A A is the frame, which may be made of cast iron or other material, and is triangular in form, with projecting ends B B, in which the horizontal shaft C has its bearings. On this shaft are placed two driving or belt-pulleys D D; also, at each end, fly-wheels E E.

F F are supports, bolted to the frame A back of the bearings, for the upper end of the vertical shaft G, at the point F', which has its step in the frame beneath, at the point A'.

The braces or supports F F in some cases may be dispensed with, and the vertical shaft can be made stationary, and the frame and the pan be made to turn on the shaft, by forming the hub longer, and making the upper end solid, for supporting the pan on the shaft.

The construction and disposition of the frame and braces or supports relative to a pan of this description are such, that much strength is obtained with less amount of material, making the machine more easily transportable to remote regions; also the frame and supports are out of the way of the movements of the pan and operator.

Below the hopper is a circular plate, I, to which are attached radial arms I' I', and from which depend rake-like teeth or pins a a a, which act as agitators or stirrers, to prevent the sand from packing near the centre of the pan, where the motion is diminishing. These teeth are set at an incline, to force the heavier particles towards the periphery of the pan.

An oil-groove, H', is made, either in the hubs of the pan or on the shaft, for lubricating the step. Above the plate is a feeding and discharging-hopper, J, from whence the pulp or tailings pass, and flow down the arm or pipe K, into an I-shaped distributor, K' K', pierced at the bottom with holes b b b and slots b' b', for the purpose of cleaning and removing obstructions, and give notice of the stoppage of the discharge through the perforations to the operator by overflowing. These distributors are made to conform to the curve of the pan, and one or more of them may be employed, stationary or movable, and, when so employed, the top of the rim of the pan is notched into a saw-like edge, c c c, in which two pawls, d d, attached to the end of the distributor, traverse, and, by means of these, each oscillation sends the distributor one notch forward in its circuit, while its inertia

causes the motion to be continuous. The centre of the hopper is a sleeve, and is stationary or turns on the shaft, and has an oil cavity, J' , in the end for lubricating the sleeve and step.

L is a descending channel or annular groove around the inner periphery of the pan, gradually declining from a certain point to an opposite or discharging-point. At this point is an opening through the bottom of the pan, for discharging the amalgam and quicksilver that may be present; also an opening above, which is provided with a small valve or gate, M , which has a hole, e , to correspond with the opening through the rim of the pan, which, by turning, brings it on a line with the said opening.

The connecting-rod N is so disposed that it accommodates itself particularly to the circular line of direction in which the pan is caused to oscillate, and is provided with a ball-crank pin, N' , at one end, and a wrist-ball pin at the other. The wrist-pin is secured to the pan through a lug, and the attachment made to the crank-shaft at the opposite end.

The pan O must be placed on a level with the central discharge, and, unless it is so placed, it is out of the question to expect it to do its duty, and while in operation the pan must be kept about half full of sulphurets, and as they accumulate over that amount, the gate or valve M is opened, when the discharging is commenced. The crank-shaft is intended to make from two hundred to two hundred and twenty revolutions per minute.

The operation of the machine is such, that grains of any kind, whatever may be their weight or size, will seek the periphery of the pan, and, unless discharged, will there remain until other grains of greater specific gravity take their place. Consequently, for a short space of time after starting the machine, the periphery will be partially filled with sand. It is therefore necessary to allow a quantity of sulphurets, sufficient to completely occupy the space, to accumulate before the gate is opened, and their discharging commenced, which may be continuous or not, according to the richness of sulphurets in the pulp or tailings. The concentrator can be set in pairs, for which a single crank-shaft will suffice.

The following are the movements which take place in my machine: The gate being closed, the pan is started by the belt-connection or otherwise, and the feed of pulp or tailings commences. Particles of all kinds rush to the periphery of the pan. The lighter are gradually displaced by the heavier particles, of which latter the larger keep at the top. This is continued until a certain depth of the fine, heavy particles has accumulated. The discharge-gate is then opened to the proper extent, and a continuous flow of this fine, heavy matter is the result. As the larger particles of the heavier matter accumulate, they will, after a time, outnumber the smaller, and will begin to find their way out with them, while the larger light particles will begin to crowd each other out at the centre with the finer portion of the waste, making my machine act in the capacity of a sizing-apparatus, as well as a concentrator, without the application of sieves or other devices to accomplish the desired object, which at best are but slow and imperfect in their operations.

Having thus described my invention, what I claim, and desire to secure by Letters Patent, is—

1. The annular groove L , declining from a certain point to an opposite or discharging-point, in combination with a vibrating or oscillating-pan or concentrator, whose surface is convex or curvilinear, as described.
2. The discharge-valve or gate M , when constructed and arranged to operate substantially as described.
3. The T-shaped distributors $K K$, pierced with holes $b b b$, and having slots $b' b'$, said distributors being either stationary or movable, and when movable the notched edge $c c c$, with pawls, or their equivalents, $d d$, operating therein for driving the said distributors, substantially as and for the purpose described.
4. The agitators or stirrers $a a$, attached to stationary or movable radial arms $I' I'$, or their equivalents, with an oscillating-pan, as described.
5. The peculiar construction of the frame $A A$, it being triangular in form, the projecting ends $B B$, for the crank-shaft, the point A' , in combination with an oscillating-pan, substantially as described.
6. The overreaching supports or braces $F F$, connecting at the point F' , and in which the upper end of the vertical shaft turns, in combination with the frame $A A$, with the projecting ends $B B$, and oscillating-pan, substantially as described.
7. The peculiar construction of the ball-crank pin N' , when employed on an oscillating-pan, substantially as described.
8. The oil-groove H , either in the hub of the pan or on the shaft G , and the oil-cavity J' , above the hopper, for lubricating the sleeve and step, with an oscillating-pan, substantially as described.

In witness whereof, I have hereunto set my hand and seal.

JOSHUA HENDY. [L. s.]
